UNITED STATES PATENT OFFICE.

ROBERT STRASSER, OF NEW YORK, N. Y.

FOUNTAIN PEN.

1,409,613.

Specification of Letters Patent. Patented Mar. 14, 1922.

Application filed August 25, 1921. Serial No. 495,384.

To all whom it may concern:

Be it known that I, ROBERT STRASSER, a citizen of the United States, and a resident of the borough of Manhattan, city, county, and State of New York, have invented certain new and useful Improvements in Fountain Pens, of which the following is a specification.

My improvements relate to the class of writing pens in which a supply of ink is contained in a reservoir formed within and by, or positioned within, the barrel or pen holder tube in a manner well known in the art, my invention being adaptable equally to the "self-filler" type of pen, or to the older and simpler form of fountain pen, with like desired results,—the object being to afford adequate and facile means whereby the proximate exhaustion of ink supply in the well may be positively ascertained by the sense of touch externally exercised; and the invention consisting primarily and essentially in the use of a float within the ink well or reservoir in conjunction with a feel-area in the side of the barrel or holding tube, substantially as herein shown, described, and claimed specifically.

In the accompanying drawings,

Fig. 1, is a sectional elevation of a fountain pen in which the holder-tube constitutes the ink font or reservoir, and to which my invention is applied;

Fig. 2 is a sectional view of the normally upper end of the pen holder-tube, inverted, and illustrating the function of my invention;

Fig. 3, is a cross section of the upper end of the holder tube taken upon plane of line 3—3, Fig. 1, and showing the float rest;

Fig. 4, is a sectional elevation of a "self-filler" type of fountain pen, embodying my invention;

Fig. 5, is a view similar to Fig. 2, showing a modification in the formation of the feel-area.

h, represents the penholder-tube provided with the usual pen-carrying plug *p*, having the customary ink guide bar *g*, etc., as heretofore. In the first three figures of the drawings the holder-tube *h*, constitutes the ink font or reservoir *r*, whereas in Fig. 4, a "self-filler" pen is shown in which the ink well or reservoir *r*, consists of a flexible rubber tube *r'*, and is provided with the customary compressor bar *c*, and manipulative lever *t*.

In either case I provide the ink reservoir *r*, with a float or follower *f*, of less specific gravity than the ink *i*, to be supplied to the said well *r*, so that the said float will rest 60 normally on top of the column of ink in the reservoir and coincide proximately with the liquid level in the latter. This float may be made of cork, or any other suitable light buoyant material and may be solid or hollow, 65 as may be found most expedient; its function being to act as an indicator of low ink level within the well, *r*, when the pen is reversed, as illustrated in Fig. 2, of the drawings.

To this end the holder tube *h*, near its upper extremity is formed with a feel area *a*, coincident with the prescribed position of the float *f*, when the pen is reversed and the ink is nearly or wholly exhausted. To insure this coincidence of float *f*, and feel area *a*, the normally upper end of the ink reservoir *r*, is formed with a float rest *r''*, so that lack of ink supply in the pen may be indicated and ascertained before the ink is 80 wholly exhausted therefrom.

The feel-area *a*, in the case of a "self-filler," as in Fig. 4, may consist simply of an aperture in the side of the holder-tube *h*, because the flexible rubber tube *r'*, acts 85 as a seal, to all intents and purposes; whereas, where the holder-tube itself constitutes the ink well, as in the other figures of the drawings, the feel-area *a*, is covered by a flexible seal *a'*, which prevents the escape 90 of ink while admitting of finger pressure to ascertain if the float is in coincidence with the feel-area, as in Fig. 2.

Where the holder-tube *h*, is made of vulcanized rubber, as is usually the case, this 95 flexible seal *a'*, may consist of a relatively soft section of rubber so formed in the manufacture of the said holder-tube *h*, as indicated in Fig. 5.

By means of my invention the pen may be 100 quickly and conveniently manipulated to ascertain if a re-filling of ink is desirable, by the simple expedient of reversal, and of finger pressure exerted through the feel area *a*. This I accomplish in a simple and inexpensive manner without altering the appearance of, or interfering with the ordinary manipulation of the pen, in any manner whatsoever. Furthermore practically no weight is added to the pen by my detective appliance,—the weight of the float *f*, being counterbalanced by the material elimi-

nated by the formation of the feel-area α . What I claim as my invention and desire to secure by Letters Patent is,

1. In a fountain pen of the character designated, the combination of an ink reservoir, a float in said ink reservoir, and a holder-tube formed with a feel-area, for the purpose described.
2. In a fountain pen of the character designated, the combination of an ink reservoir, a float in said ink reservoir, and a holder-tube formed with a feel-area, said ink reservoir being also formed with a float rest, for the purpose described.
- 15 3. In a fountain pen of the character des-

ignated, the combination of an ink reservoir, a float in said ink reservoir, and a holder-tube formed with a flexibly sealed feel-area, for the purpose described.

4. In a fountain pen of the character des- 20
ignated, the combination of an ink reservoir formed with a float rest, a float in said ink reservoir, and a holder-tube formed with a flexibly-sealed feel-area, for the purpose set forth.

ROBERT STRASSER.
